UNITED STATES PATENT OFFICE.

M. J. GOODWIN, OF BOSTON, MASSACHUSETTS.

IMPROVED RAILWAY-TRACK CLEARER.

Specification forming part of Letters Patent No. **58,634**, dated October 9, 1866.

To all whom it may concern:

Be it known that I, M. J. GOODWIN, of Boston, in the county of Suffolk and State of Massachusetts, have invented an Improved Track-Clearer for Horse Railway-Cars; and I do hereby declare that the following, taken in connection with the drawing, which accompanies and forms part of this specification, is a description of my invention sufficient to enable those skilled in the art to practice it.

The invention relates to a provision in horse railway-cars for removing obstructions from the tracks upon which they run, and consists in attaching to and in front of the brakes clearers supported directly over but out of contact with the surface of the rails, and in front of the car-truck.

The drawing represents one end of a car-truck with my invention applied thereto, A showing a side elevation, and B an end view of the same.

a denotes the truck-frame; *b*, the journal-boxes; *c*, the wheels, and *d* the brakes, the construction and arrangement of these parts being the same as in ordinary cars.

To each brake *d* is jointed an arm or frame, *e*, swinging loosely in a vertical direction and carrying at its front end a roller or clearer, *f*, as seen in the drawing.

From each arm, near its roller, a chain, *g*, extends, connecting the arm to the journal-box *b*, the chain holding the roller or clearer a slight distance above the surface of the track-rail, the roll being by the connection held in position relatively to the surface of the rail,

and consequently kept out of contact with the rail, whereas, if suspended only from the car-truck, it would sway vertically with such truck. By hinging the arm directly to the brake, whenever the clearer strikes an obstruction it presses the brake against the tread of the wheel, and tends to stop the cars, while, from the form and disposition of the clearer, the obstruction is either thrown from the track, or up on to the top of the arms *e*, the roller turning and having a tendency to roll the object on to the said arms.

Loss of life or limb is constantly occurring upon the horse railway-tracks of cities and large towns from persons being thrown under the wheels; but with my arrangement it will be obvious that a person cannot come into contact with the wheel, but will, if struck, be either thrown from the track or up onto the clearer-arms.

The mechanism is inexpensive, and may be applied at very small cost to the cars in general use without any alteration or modification in their general construction.

I claim—

Combining with the car-truck and brakes of a railway-car the clearers hung from the brakes in front of the car-truck and at a short distance above the surface of the track-rails, substantially as described.

M. J. GOODWIN.
